United States Patent Office

Des. 184,991
Patented Apr. 28, 1959

184,991

BOTTLE

Floyd D. Flexon, Godfrey, Ill., assignor to Owens-Illinois
Glass Company, Toledo, Ohio, a corporation of Ohio

Application March 20, 1957, Serial No. 45,352

Term of patent 14 years

(Cl. D58—8)

Fig. 2.

Fig. 3.

Fig. 1 is a side elevational view of a bottle showing my new design.

Fig. 2 is a fragmentary side elevational view taken at right angles to Fig. 1.

Fig. 3 is a top plan view showing the bottle neck and handle.

The dominant features of my design reside in the portions shown in full lines.

The bottle is shown broken away in Fig. 2 for convenience of illustration.

I claim:

The ornamental design for a bottle, substantially as shown and described.
